UNITED STATES PATENT OFFICE.

HEINRICH WALther, OF WEISSENFELS, GERMANY, ASSIGNOR TO THE FIRM OF NOLLESCHE WERKE, ERNST NOLLE, OF WEISSENFELS, SAXONY, GERMANY.

LASTING AND NAILING MACHINE.

1,110,171.

Specification of Letters Patent.

Patented Sept. 8, 1914.

Application filed December 10, 1906, Serial No. 347,129. Renewed April 29, 1914. Serial No. 835,334.

To all whom it may concern:

Be it known that I, HEINRICH WALther, a subject of the King of Prussia, German Emperor, residing at Weissenfels, a. S., in the Province of Saxony, German Empire, have invented certain new and useful Improvements in Lasting and Nailing Machines; and I do hereby declare the following to be a full, clear, and exact description 10 of the invention, such as will enable others skilled in the art to which it appertains to make and use the same.

This invention relates to the class of lasting machines for stretching the uppers of 15 shoes over the last and fastening the same upon the insole, in which more than one pair of pincers simultaneously come into action and differs from the known machines of the Paine and Chase system in that according to the present invention the last is 20 placed with the sole downward and that the pull of the pincers is exercised first downwardly and then inwardly. The upper is positioned upon an upright last and is 25 visible to the attendant who can thus closely observe the action of the pincers and control the stretching of the upper and avoid any displacement of it on the last.

It is an important feature of this machine 30 that the pincer carriers are so constructed as to form at the same time the wipers on their upper surface which wipers move inward together with the pincers. These pincer carriers hold also the tack drivers, 35 so that they move simultaneously inward after the upper has been stretched, and consequently causes the tacks to be driven into the insole always in a precise distance from the edge of the upper. The pincer carriers 40 form therefore not only the guides for the pincers, but simultaneously the upper wipers themselves, which have hitherto been constructed separately, and also themselves form the tack drivers.

The invention may be either arranged as 45 a lasting machine with any convenient number of side and toe grippers or only as a pulling over machine to be used in connection with a lasting machine, which latter 50 completes the tacking of the pulled over shoe.

The pulling over machine is provided with preferably only two side grippers, which work together with one pair of toe 55 grippers. The latter is preferably con-

structed so that it may be opened and closed by hand. The last with the upper having been placed on the toe-rest, the projecting edge of the upper is grasped by the toe-pincers. This done the last is pressed down 60 until it rests upon the heel-rest. This causes the toe-part to be pulled over in practically exactly the same manner as if done by hand.

In the accompanying drawings the arrangement is illustrated as a pulling over machine with two opposite side grippers and one toe gripper.

Figure 1 shows a side elevation of the pulling over machine in a position of rest 70 with the closed toe gripper shown in dotted lines. Fig. 2 is a front elevation of the machine likewise at rest with the last support left out. Fig. 3 is a horizontal section on the line A—B of Fig. 1 the lower parts 75 of the machine not shown. Fig. 4 is a vertical section on the line C—D of Fig. 1 and shows the clutch for operating the mechanism. Fig. 5 is a horizontal section on the broken line E—F of Fig. 1. Fig. 6 is a horizontal section on line G—H of Fig. 1. Fig. 7 shows the position of the cam wheel with its two actuating grooves for the 80 pulling over frames for imparting to the grippers an up and down and a rocking 85 movement respectively. Fig. 8 is a longitudinal section through the operative parts of the machine after the first stage of operation *i. e.*, after the grippers have been moved downward. Fig. 9 indicates the 90 position of the cam grooves corresponding to the said stage of operation. Fig. 10 is a longitudinal section through the machine at the end of the second stage of operation, when the pincer carriers have been rocked by a frame under 95 the insole and have laid and fastened the upper on the insole. Fig. 11 illustrates the position of the side-grippers according to Fig. 10, the front gripper not shown. Fig. 100 12 indicates the position of both the cam grooves of the cam wheel corresponding to the second stage of operation. Fig. 13 is a view of the side pincers open. Fig. 14 is a view of the side pincers closed.

In the pulling over machine according to the present invention the margin of the toe part of the upper is at first introduced between the jaws of the open front grippers. These grippers are closed after the last de- 110

signed to shape the upper has been brought to bear against the toe rest. The last is thereby positioned so as to form an angle with the horizontal plane of the machine bed. By pressing down the last until its heel part lies upon the heel rest the upper is stretched taut at the toe, just as in hand lasting, so that a warping of the upper during the operation of the side grippers is rendered practically impossible. The instep is held fast by means of the instep loop, and the last is held fast by means of holder placed over it. The leather now projects between the jaws of the side pincers. On pressing down a treadle the machine is started. This treadle works in such a manner that by pressing down the treadle, the machine is turned for only one third of a revolution, then is automatically put out of gear.

During the first third of a revolution the cam grooves cause the jaws of the side pincers to close, the side and toe pincers are moved downward in their carriers and thereby stretch the gripped margin of the upper. This downward movement of the pincers is rendered a yielding one by means of interposed springs.

The second working stage begins with the second depression of the treadle. The pincer carriers with their wiper plates and pincers are rocked inward by a frame moving upward, and moves underneath the sole. At the end of this stage the hammer drivers carried by the pincer supports, come into operation and drive the tacks, previously inserted in a suitable manner into corresponding holes, into the marginal part of the upper and the insole.

At the third depression of the treadle, the third working stage commences. The frame imparting the rocking movement to the pincer carriers and pincers is lowered and the carriers are drawn outward by springs into their normal position. The pincer frame rises again so that the side pincers are again opened while the tack drivers are put in gear for the new operation, so that the machine is brought back to its initial position. It then remains only to open the toe pincers by raising their hand lever, and to swing back the holder which retains the last in order to release the pulled over shoe.

The machine comprises the following arrangements: The driving shaft 2 is journaled in the machine frame 1 and carries the belt-pulley 4 provided with the clutch 3, and the disengaging gear. The latter is actuated by a treadle 5 and works with wedge plane 6 against a wedge plane 7 of a box 8 thereby connecting the belt pulley with the coupling fastened on the driving shaft 2 and simultaneously disengaging by means of the rack 9 and arm 10 the roller 12 placed on the lever 11 from one of the notches 13, 13^a, 13^b

of the disk 14. When the treadle 5 is released the roller 12 slides upon the periphery of the disk 14 until it automatically engages with the next of the notches 13, 13^a or 13^b.

The intermittent rotary movement thus effected is transmitted to the cam disk 15 on the end of the shaft, the said cam disk having a cam groove 16 for moving the pincer frame *a*, a cam groove 17 for moving the pulling over frame *b* and on its circumference a recess 18 for actuating the nail driving frame *c*. These detailed arrangements will be hereinafter separately described.

The last support.—To hold the last the machine frame 1 is provided with a table like part 19 upon which the toe rest 20 and the heel-supporting-screw 21 are adjustably arranged. At the rear the last is held by a heel support 22 adjustable in the vertical and horizontal direction by a clamp 23 and a toothed rack 24 respectively. The toothed rack 24 is suitably adjusted by means of the pinion 25 and hand lever 26 and held in position by the pawl 27 and the pawl lever 28. During the pulling-over operation the shoe is held in place by a loop 29 on the lever 30 pivoted in the machine frame, the said loop being placed over the ball of the last.

The pincer devices.—The pincers grasp the upper and stretch it and while moving downward rock toward each other together with their carriers under the insole and hold the upper fast until the nail drivers likewise mounted in the carriers have driven in the tacks, and all parts of the machine return to their normal position. The pincers are placed on their pincer carriers, the toe pincers on the pincer support *d* and the side pincers on the pincer carriers *e*. The pincer carrier *d* rests vertically revoluble on the pivots 31 of the brackets 32 fixed on the machine frame 1. The pincer carriers *e* are likewise vertically revoluble and rest upon the pivots 33.

The side pincer carriers may be differently adjusted with relation to the carrier *d* by the following arrangement: The pivots 33 are provided with sockets 34 engaging by an external screw thread with a female socket 35 in the machine frame. On the pivots 33 are toothed wheels 36 fastened to the sockets 34. The teeth of the toothed wheels 36 gear with a rack 37 movably arranged in the rear of the machine and actuated by a pinion 38. The latter is suspended in the bearing 39 on the pivots 40 and revolved by the hand lever 41. The socket pairs 34 and 35 are reversely threaded on either side of the machine. By moving the lever 41 in either direction the side pincer carriers *e* are moved laterally toward or away from the toe pincer.

For moving the side pincers uniformly

relative to the projecting edges of the upper, screw nuts 42 and 43 are arranged upon the threaded parts of the pivots 33 which adjust the side pincers against the tension of the springs 44. To regulate the side pincers therefore the nuts 42 and 43 are used in combination with the springs 44.

The pincers therefore are movably supported in the pincer carriers *d* and *e* and have fixed jaws *f* and movable jaws *g*. The jaws *f* project from guide-blocks *h* provided with sleeves *i* and bear against the flat portions *k* of the pincer carriers *d* and *e*. Beneath the guide blocks *h* springs 45 are provided which tend to move said guide-blocks upward. The movable pincer jaw *g* is provided with a lever arm 46 and terminates in a segmental-gear engaging with a rack bar 47 passing through the sleeve *i*. The rack bar is connected by means of the link 48 provided with a universal joint, with the plunger 49. This plunger passes through the pincer frame *a* which controlled by the cam 15 moves up and down in the guides 50 of the machine and lifts and lowers the link 48. Upon the plungers 49 springs 51 are mounted the tension of which may be regulated by adjusting the nut 52. The springs 51 render the movement of the rods 47, 48, 49 yielding so as to make the pull of the grippers elastic. The pincer frame *a* has a roller 53 operating within the groove 16 of the cam 15. This produces the following result. When the cam groove 16 causes the frame *a* to descend the rods 47, 48 and 49 are pulled down and by means of the gears 46 and 46^a, the pincers are first closed to grasp the upper (see Figs. 13 and 14); then by the continued descent of the frame *a* the sleeve *i* moves with the guide block *h* also downward under the tension of the springs 51 thereby stretching the upper, the pull being a yielding one owing to the said springs (Fig. 8). In the third working stage the cam roller 53 and frame *a* and therefore also the rods 47, 48 and 49 rise, the pincers with the sleeves *i* and guide blocks *h* are moved outward and the pincer jaws open.

To effect the closing of the toe-pincers in their normal position the segment 46 of the movable jaw is suitably set in relation to the bar 47, being under spring tension. The plunger 49 of the toe pincers rests upon the lever 54 fulcrumed at 55. On lifting this lever the jaws *f*, *g* of the toe pincers are opened by means of the rods 47, 48 and 49. The lever 54 is yieldingly held by the spiral spring 56. The actuation of the pincers by cam grooves in the three different working stages is illustrated in Figs. 7, 9 and 12.

The rocking of the pincer carriers in order to pull the edge of the upper over the last and the insole.—The pincers having grasped and drawn downward the upper (see the

groove 16 in the normal position Fig. 7 and in the first working stage Fig. 9) the pincer carriers *d* *e* are to be moved underneath the insole. To do this the pulling over frame *b* operates. This frame is moved by the cam 70 groove 17, into which projects a roller 57 on the plate *b'* sliding in a vertical guide of the machine. The frame *b* bears with rollers 59 against inclined shoulders 60 of the carriers *d* *e*, the said rollers being arranged on bolts 61 which may be adjusted by the set screws 62 in order to move the carriers inward to a greater or less degree. The springs 63 on the frame *b* draw the carriers *d* *e* into their position of rest when the frame *b* descends.

The operation of the device is as follows: The frame *b* rises upward during the second working stage (Figs. 10-12) and presses against the inclined shoulders 60 and rocks 85 the pincer carriers which are fulcrumed on the bolts 31 and 33 inward. The upper being fastened to the insole in a manner hereinafter described, the frame *b* moves downward and the springs 63 withdraw the pincer 90 carriers to normal position.

The tacking mechanism.—In the upper plate *k* of the carriers *d* *e* are arranged tack receiving holes and there is fitted in these holes the drivers 64 fixed on the nail blocks 95 65. The latter are guided by the rods 66 in the pincer carriers and are connected by bars 67 with the tack driving frame *c*. The block 65 may be adjusted by the set screws 68. The tack driving frame *c* slides in 100 guides 69 of the frame 1 and its roller 70 bears on the periphery 71 of the cam 15. The roller 70 enters into the recess 18 and permits the operation of the tacking device. Beneath the frame *c* and the guide plate *c'* 105 springs 72 are adjustably arranged on a shaft and may be put under suitable tension by the regulating device 73. These springs act upon the arm 74 which presses by means of the link 75 against the lower 110 part 76 of the guide plate *c'* and force the said frame and its associated nail block upwardly to drive and seat the nails disposed in the block *k*. To render this action elastic the stop 77 is provided with springs 78. The 115 tacking devices of all the pincers are identical, the movement of the cam and associated parts being shown at Fig. 12.

Projections 79 on the pincer carriers *d* and *e* guide the edge of the sole as the pincer 120 carriers move inward, and these projections 79 may be adjusted according to the shape of the last.

The entire operation of the machine will now be described with reference to the position of the cam 15 shown in Figs. 7, 9 and 12.

In the position of rest the side grippers are open, and the toe-pincers closed. By lifting the hand lever 54 the toe pincer is 130

opened and the toe portion of the upper is first grasped, whereupon the shoe is forced down on the heel-supporting screw 21 and is so held by means of the stirrup 22, that it stands in alinement with the machine. The loop 29 is lowered and by pressing down the treadle 5 previously brought to its normal position by the spring 80, the inclined surfaces 6, 7 of the clutch are engaged, the roller 12 released and the machine set in motion. The machine now performs the first working stage *i. e.* the cam 15 comes from the position of rest I (Fig. 7) into the first position of operation II (Fig. 9) and the grooves 16, 17 and the recess 18 of the cam 15 show the position illustrated in Fig. 9. The frame *a* is thereby moved downward and the side-pincers closed (the toe-pincer being already closed upon the release 20 of the hand lever 54), and all the pincers stretch the upper, the last lies upon the toe support 20 and heel-screw 21 and is held fast by the stirrups 22 and 30. The rollers 59 of the frame *b* retain their position, as the groove 17 here runs concentrically of the disk (Figs. 7 and 9). In the second depression of the treadle 5, whereby the actuation by the inclined surfaces of the wedges 6, 7 and the moving out of the roller 12 by falling into the recesses 13, 13^a 30 13^b is repeated, the frame *b* is caused to swing inwardly by means of the inclined shoulders 60 the pincer carriers *d* and *e*. The roller 57 runs in the groove 17 (Fig. 12) 35 while the roller 53 of the pincer frame *a* passes in its concentric path from the position II into the position III. Thereby the inclination of the pincer-carriers is effected, whereupon the roller 70 of the nail-driving frame *c*, *c'* enters in the recess 18 of the cam 15 and the spring 72 pushes the nail-drivers upward to complete the tacking.

The last depression of the treadle 5 causes the cam 15 to move from the position III 45 into the position I, which is the normal position. The rollers 53, 57 and 70 guided by grooves 16, 17 and recess 18 respectively move the pincer frame *a* upward to open and to lift the side-pincers and the frames *b* and *c* to bring the carriers back from the inclined into a straight position and put the nailng apparatus under tension. To remove the pulled over shoe, it is only necessary to lift the pincer lever 54 and to swing 50 55 back the stirrups 29, 30.

What I claim is:—

1. In a machine of the class described, pivoted pincer carriers, of pincers slidably mounted in the pivoted carriers, means for positively tilting the carriers and separate means for moving the pincers downward.

2. In a machine of the class described, pivoted pincer-carriers, pincers slidably mounted in the said carriers and nailng

rods likewise slidably mounted in the pivoted carriers.

3. In a machine of the class described, pivoted pincer carriers, pincers and nailng rods, both slidably mounted in the carriers, and wiper plates mounted upon the carriers.

4. In a machine of the class described, pivoted pincer carriers, pincers slidably mounted in the said carriers, and springs supporting the pincers upon the pivoted carriers.

5. In a machine of the class described, pivoted pincer carriers, pincers slidable in the said carriers and comprising stationary and movable jaws, racks slidably mounted adjacent the movable jaws, gear teeth upon the movable jaws interengaging with the racks, and a vertically moving part engaging the racks and adapted to close first the pincers and then to pull them down.

6. In a machine of the class described, pivoted pincer carriers, pincers slidable in the said carriers and comprising stationary and movable jaws, racks slidably mounted adjacent the movable jaws, gear teeth upon the movable jaws interengaging with the racks, and a vertically moving part engaging the racks and adapted to close first the pincers and then to pull them down, and springs between the vertically moving part and the slidable racks for yieldingly moving the pincers.

7. In a machine of the class described, pivoted pincer carriers provided with inclined shoulders, pincers slidable in the said carriers, a yoke mounted adjacent the pincer carriers, and movable relative thereto to move the carriers upon their pivots and to lay the upper stretched by the pincers upon the insole.

8. In a machine of the class described, pivoted pincer carriers provided with inclined shoulders, a yoke movable relative thereto, friction rollers upon the yoke adjacent the carrier shoulders, and means for adjusting the rollers upon the yoke against the inclined shoulders of the pivoted carriers.

9. In a machine of the class described, a cam disk provided with a plurality of cam grooves, pivoted pincer carriers having inclined shoulders, pincers carried by and movable relative to the pincer carriers, a vertically moving part controlled by one groove of the cam for moving the pincers relative to the pincer carriers, and a yoke adjacent the inclined shoulders of the pincer carriers and movable relative thereto and controlled by another of said cam grooves for tilting the said carrier upon their pivots.

10. In a machine of the class described, pivoted pincer carriers, a grooved cam, a plurality of pincers carried by and movable relative to the pincer carriers, one vertically

moving part controlled by said cam for moving all the pincers relative to the pivoted carriers, and means permitting the manual operation of the toe pincers independently of the cam groove.

11. In a machine of the class described, vertically moving parts, pivoted pincer carriers, a yoke adjacent the pincer carriers and movable relative thereto, pincers slideable in the said carriers and connected to one of said vertically moving parts, nailing rods slideable in the said carriers and carried by another of said vertically moving parts and a cam disk provided with three cams connecting the said yoke and the two vertically moving parts.

12. In a machine of the class described, a framework, side and toe pincer carriers mounted therein, adjusting screws for varying the interval between the toe pincer carriers and the side pincer carriers, and resilient means for holding the carriers last mentioned in such adjusted position.

13. In a machine of the class described, a frame, pincer carriers pivoted upon the frame, resilient means for holding the pin-

cer carriers yieldingly spaced, and means to vary the normal interval between the pincer carriers.

14. In a machine of the class described, a frame, pincer carriers pivoted upon the frame, a resilient member adapted to hold the pincer carriers normal and yieldingly spaced, and means engaging the pivots adapted to vary the normal interval between the pincer carriers.

15. In a machine of the class described, a frame, means mounted upon the frame for supporting lasts of various sizes, pincer carriers pivoted upon the frame, means to vary the interval between the pincer carriers to correspond with the sizes of lasts, and resilient means positioned to hold the pincer carriers normally spaced at the predetermined interval.

In testimony whereof I affix my signature in presence of two witnesses.

HEINRICH WALTER.
